(57) **CLAIM**

The ornamental design for a fish shaped bottle opener, as shown.

DESCRIPTION

FIG. 1 is a front perspective of my new design for a fish shaped bottle opener.

FIG. 2 is a right side plan view of the bottle opener shown in FIG. 1.

FIG. 3 is a left side plan view of the bottle opener shown in FIG. 1.

FIG. 4 is a top plan view of the bottle opener shown in FIG. 1.

FIG. 5 is a bottom plan view of the bottle opener shown in FIG. 1.

FIG. 6 is a front plan view of the bottle opener shown in FIG. 1.

FIG. 7 is a back plan view of the bottle opener shown in FIG. 1.

FIG. 8 is perspective view of the bottle opener shown in FIG. 1 being used to open a bottle using the first opening location; and,

FIG. 9 is a perspective view of the bottle opener shown in FIG. 1 being used to open a bottle using the second opening location.

The broken line showings of a bottle in FIGS. 8 and 9 are for illustrative purposes only and form no part of the claimed design.
